FLOATING GAME GOAL

Robert W. Wathen, Wortman Road,
Evansville, Ind. 47711

Filed Jan. 30, 1967, Ser. No. 5,604

Term of patent 14 years

(Cl. D34—5)

FIG. 1 is a top plan view of a floating game goal showing my new design.

FIG. 2 is a view in elevation of the claimed design, looking either from right to left or from left to right in FIG. 1; and,

FIG. 3 is a view in front elevation of the claimed design, where the view in back elevation would be the same.

I claim:

The ornamental design for a floating game goal, as shown and described.
